UNITED STATES PATENT OFFICE.

ALBERT HENNIG, OF BIELEFELD, GERMANY, ASSIGNOR TO ANKER-WERKE AKTIEN-
GESELLSCHAFT, OF BIELEFELD, GERMANY.

THREAD TIGHTENER.

Application filed May 1, 1926, Serial No. 106,077, and in Germany November 4, 1924.

The present invention relates to improvements in thread tighteners, and is particularly adapted for use with buttonhole-sewing machines having automatic thread cutting 5 shears after cutting the threads are swung sidewise out of the cloth pressure apparatus.

With machines of this character, it is essential that the thread be firmly tightened 10 at the time when the shears holding the cut thread are swung back in order to take as much loose thread as necessary for the beginning of the next buttonhole; that is to say, to have as much loose thread as the 15 shears need for their swinging movement, and as is necessary for the proper functioning of the first stitch at the beginning of the next buttonhole.

In accordance with the present invention 20 I accomplish this result by the provision of a thread tightening lever, to which a swinging movement is given when the cloth clamp is opened after the cutting of the upper thread. This lever draws the thread off to 25 the side between the pressure apparatus and the thread carrier after the clamping of the pressure apparatus is relieved.

I have shown the apparatus as attached 30 to a conventional type of buttonhole sewing machine, although obviously it might, with slight variations, be attached to other sewing machines.

The invention may be more fully understood from the following description in connection with the accompanying drawings, 35 wherein—

Fig. 1 is a view in side elevation of a sewing machine embodying the present invention.

Fig. 2 is a fragmentary side elevation 40 looking at the machine from the opposite side.

Fig. 3 is a sectional plan view through the machine.

Fig. 4 is a plan of the head of the machine.

The upper thread 10 runs in the well known way, from the tension discs *a*, over a fixed thread hook *r*, and tightening spring 50 *u*, to the thread carrier *q* swinging up and down. I provide means for relieving at timed intervals, the thread clamping action of the tension discs *a*. This means may conveniently be in the nature of an arm *b* mounted on a rock shaft *c*, journalled trans-

versely of the head of the machine. The arm *b* is provided with a wedge shaped nose *b'* adapted to enter between the clamping device *a*, consisting of two discs *a'* *a''*, having conical flanges, loosely arranged on 60 a fixed threaded pin *a''* and pressed together by a conical spring *a''*, against which the curled nut *a''* of the pin *a''* works. When the nose *b'* of the arm *b* is pressed between the two discs *a'* and *a''*, the tension of the 65 thread 10 is relieved.

The other end of the rock shaft *c* carries an arm *d*, pivoted as at *e*, by a ball and socket joint to the forked end *f'* of a curved arm *f*. Arm *f* is connected to one end of a 70 shaft *g*, journalled longitudinally of the machine in suitable bearings *g'*. The opposite end of the shaft *g* is rigid with a crank arm *h* carrying at its free end a pin *i*, which can be shifted against the pressure 75 of a spring (not shown) arranged in boss *h'* of the arm *h*. The pin *i* rests against the rear side of an arm *l* connected with a not shown lever for the knife for cutting the buttonhole and this arm *l* guides the 80 stop pin *x* of the stopping and starting lever *k*. To the crank arm *h* is connected a spring *m*, the other end of which is fastened to the under end of the stopping and starting lever *k*. This arrangement is generally known, so that a further description 85 seems not to be necessary.

Arm *l* is moved downward in the well known way, when the stopping and starting lever *k* is swung backwards after a buttonhole is finished, thus permitting the pin *i* under the influence of its spring to catch over the arm *l*. When the stop pin *x* moves upward again in order to stop the main driving shaft, the pin *i* is taken along, and the 90 crank *h* is swung upwards, so that by shaft *g*, curved arm *f*, arm *d* and shaft *c* the arm *b* is swung against the tension device *a*, so that the wedge shaped nose *b'* of the arm *b* is pressed between the tension discs *a'* *a''* 100 and spreads them, whereby to relieve tension on the thread 10.

The shaft *c* also carries a tightening lever *o*. This lever is rotatably mounted on the shaft, and is normally spring held in the 105 position of Fig. 2 by a coiled contractile spring *o'*. The lever *o* carries at its upper end a strap *p*, through which the thread 10 passes. The lower end of lever *o* rests upon the forward end of the tilting cloth clamp *n*, 110

beneath which the automatic shears *u* of conventional construction are disposed.

After finishing the buttonhole, the rear end of the cloth clamp is pressed downwardly in the conventional manner tilting the front end upwardly to permit movement of the cloth. At this time the shears are actuated to cut the thread. Simultaneously the lever *o* is moved to the dotted line 10 position of Fig. 2, whereby the thread strap *p* draws the thread sidewise between the tensioning discs *a* and the thread carrier *q*, providing considerable slack in the thread. This slack accommodates for the return 15 movement of the shears *u*, when swinging back from the cloth pressure apparatus after cutting the thread.

Various changes and alterations might be made in the general form and arrangement 20 of parts described without departing from the invention. Hence I do not wish to limit myself to the details set forth, but shall consider myself at liberty to make such changes and alterations as fairly fall within the 25 spirit and scope of the appended claims.

I claim:

1. The combination with a sewing machine including a tilting cloth clamp, of a

pivoted thread pulling lever having at one end a member through which the thread 30 passes and having its other end normally resting directly on the cloth clamp and actuated by movement thereof to produce slack in the thread.

2. In a sewing machine, the combination 35 with a cloth clamp, of a pivoted thread pulling lever having its lower end normally resting on the cloth clamp and actuated thereby, and a loop carried by the upper end of the said lever and through which the 40 thread passes.

3. In a sewing machine, the combination 45 with a cloth clamp and a thread tensioning device, of a rock shaft, an arm mounted on the rock shaft for rendering the tension device inoperative, and a pivoted and spring pressed thread pulling lever mounted on the 50 said rock shaft and having its lower end engaging the cloth clamp and actuated thereby, and a loop at the upper end of the said lever and through which the thread passes.

In testimony whereof I have signed my name to this specification.

ALBERT HENNIG.
